FRANK W. MERRITT AND ALFRED E. WATTS, OF DULUTH, MINNESOTA.

MEANS FOR AUTOMATICALLY REGISTERING A SHIP'S DRAFT.

1,380,575.

Specification of Letters Patent. Patented June 7, 1921.

Application filed November 17, 1919. Serial No. 338,675.

To all whom it may concern:

Be it known that we, FRANK W. MERRITT and ALFRED E. WATTS, both citizens of the United States, and both residing at Duluth, 5 in the county of St. Louis and State of Minnesota, have jointly invented certain new and useful Improvements in Means for Automatically Registering a Ship's Draft, of which we do hereby declare the following 10 to be a specification.

Our invention relates to devices for automatically registering a ship's temporary draft and has for its object the provision of means for automatically making such registration at any or all times in the pilot 15 house, navigating room or other suitable place on the vessel, thus avoiding the necessity of reading depth-marks upon the outside of the hull or of measuring the ship's freeboard from the deck and thus calculating 20 the draft. Our invention is particularly convenient for use during the operation of loading, at which time it is desired to so distribute the load as to properly trim 25 the ship, and at the same time to determine when the predetermined or permissible draft limit has been reached at the bow, stern, and amidships. Another object of our invention is to provide inboard means for determining 30 the draft factor for calculating the temporary displacement of a ship from which the dead weight of the ship, or of the ship and cargo may be figured. If desired one device embodying our said invention 35 may be installed on the starboard side of the ship, and another on the port side, for the purpose of furnishing separate draft readings for the opposite sides of the ship, so that the vessel may be leveled athwartships while she is being loaded.

With these and other objects in view, our invention consists of the constructions, combinations and arrangements of parts hereinafter described and claimed.

In the drawings, Figure 1, is a diagrammatic view showing the hull of a ship with deck houses thereon, and showing the general arrangement of the hereinafter described pressure cylinders, gages and pipe lines embodied in our invention. Fig. 2 is a side elevation of our said invention, partly in central longitudinal section and partly broken away, showing also in vertical longitudinal section a portion of the ship's bottom. Fig. 3 is a central vertical longitudinal section through a portion of a modified

form of our device showing the hereinafter described separate cylinders.

In the drawings, 1 is the hull of the ship, of which 1^a is the bottom and 1^b a room in a 60 deck house. The drawings, Fig. 1, show three installations of our invention, as at A, B, and C. These installations are respectively for registering the draft at the bow and amidships and at the stern. There 65 is no difference in their structural features, and therefore only one of them will be described in detail, as for example the midship installation shown in Fig. 2.

Referring to Fig. 2, 1^a is the bottom of the 70 ship which is apertured in any suitable manner at 1^c, by a group of small holes or by a single larger opening as desired, which aperture is covered by and communicates with a pipe line 2, which at a point near its 75 lower end is provided with a gate valve 2^a, by which it may be closed during the assembly or repair of parts at the opposite or forward side of said gate. Interposed in said pipe line at the upper side of said 80 gate is a chamber 3, containing a strainer of any suitable construction, preferably comprising a series of perforated disks or cones 3^a, of metal, adapted to strain the inflowing water. Said pipe 2, terminates at 85 one end in a pressure cylinder 4, of any suitable structure, containing a piston 5. In order to translate the forward pressure of sea water upon the piston 5 into terms of draft-feet upon the hereinafter described 90 gage, we prefer to reduce the bore of said cylinder at its upper or forward end as at 4^a and to correspondingly reduce the forward end of said piston as at 5^a, the reduced 95 end of the piston fitting closely into the reduced bore of said cylinder, and the larger end of the piston fitting closely into the large end of the bore of said cylinder. The difference in the diameters of said bores is approximately as 2.3 to 1. Separate cylinders 100 of different diameters may of course be placed end to end and substituted for the single cylinder with a large and reduced bore. In Fig. 3 such separate cylinders are shown in central vertical longitudinal section, as at 4^d and 4^e, respectively.

No water is permitted to pass the larger end of said piston 5 from the sea, and no fluid from any point forward of said piston is permitted to pass the reduced end 5^a of 110 said piston. It will be observed that at times during the stroke of said piston 5, there will

be a space 4^b between the forward face of the enlarged end of said piston and the opposing end of the large chamber of said cylinder. To prevent the formation of a 5 vacuum in said space, and to prevent the imprisonment and compression of air therein, according as the piston is moving backward or forward, a vent 4^c is provided communicating with said space and with the 10 free atmosphere. Communicating with said structure at any suitable point between the rear end of said piston and the forward end of said strainer is a blow-out pipe 6, leading to the ship's boiler (not shown) or 15 pump, or other source (not shown) of fluid under pressure for the purpose of blowing any mud or other impurities or obstructions out of the intake end of said system. A check valve 6^a is interposed in said blow-out 20 pipe near its lower end to prevent the sea water from passing toward the boilers or other source of fluid under pressure, while permitting steam or other fluid to flow toward the open end of system. Above the 25 check valve is a gate valve 6^b.

Communicating with the forward end of the reduced bore 4^a of said cylinder 4 is a pipe line 7 extending forward or upward to any location on the vessel at which it is 30 desired to register the draft, as, for example, into said room 1^b. Near its upper end said pipe line divides into three branches, as 7^a, 7^b and 7^c, respectively. One of said branches as 7^b, is provided with a terminal pressure 35 gage 8 of any suitable structure for recording internal pressures of fluid character, such, for example, as are well known to the art, and we believe it requires no further description here. We prefer, however, to 40 provide a double row or circle of registering marks upon the dial of said gage, one of which will show the correct registration when the ship is in salt water, and the other of which will show the correct registration 45 when the ship is in fresh water. Between said gage and the main stem of said pipe 7, a gate valve 9 is preferably interposed for shutting off from the gage 8 any excessive pressure which may be occasioned by 50 the pounding of the ship in a heavy sea. Another of said branches, as 7^c is provided with a terminal cup 10, for filling said pipe line 7 and said branches 7^a, 7^b and 7^c; said cup is adapted to be closed by a tight cover 55 10^a. The remaining one of said branches, as 7^a, is provided with a terminal pressure chamber 11, containing a piston 11^a of any suitable construction adapted to be arbitrarily operated by any suitable means, as 60 by a manually operatable screw 11^b extending through the cover 11^c of said chamber. Said pressure chamber is for the purpose of increasing or diminishing the pressure on said gage of the fluid in said pipe line 7 65 (by increasing or diminishing the cubical

capacity of that part of chamber 11 lying below the piston 11^a) to compensate for any leakage which may have occurred in said pipe line, or to restore the proper pressure when for any reason due to excessive 70 or inadequate pressure the gage does not register correctly. Said pressure chamber 11 may be placed at any convenient point on the pipe line 7. Gate valves, as 7^d and 7^e 75 are preferably interposed in said branch 7^c and in the main stem of said pipe 7, respectively, and at any suitable points where it may be desired to place them in order to close the system at one end for the purpose 80 of repairs or otherwise. The pipe line 7 and its branches are preferably filled with a non-congealing fluid of any suitable character, such as glycerin and alcohol, or a medium lubricating oil (as sperm oil) and turpentine; although other fluids may be 85 used, especially in warm climates. The pipe line 2, is of course filled with water in communication with the body of water in which the ship floats. The intermingling of the water in pipe line 2 and of the fluid in pipe 90 line 7 is entirely prevented by the piston 5—5^a.

The opening in the bottom of the ship at the mouth of pipe 2, is preferably covered or protected by a perforated convex cover 95 or shoe 12, closed toward the bow and preferably slightly open toward the stern, said shoe or cover being for the purpose of preventing as far as possible the entrance of mud and sand and other coarse impurities. 100

In operation, the pressure of the sea water against the piston 5 increases as the ship is loaded and sinks deeper into the water. Said pressure is communicated by said piston to the column of fluid in pipe line 7 105 and by said fluid to the pressure gage.

Having now described our invention, what we claim is—

1. In a device for registering the temporary draft of a vessel, the combination with the hull of a vessel having an aperture formed through its bottom communicating with the free water in which the ship floats, of a water conductor covering said opening and communicating therewith at one end, a pressure cylinder communicating at one end with the opposite end of said conductor, a floating piston within said cylinder, a fluid container communicating at one end with the opposite end of said pressure cylinder, said fluid container communicating at its opposite end with an internal fluid pressure gage, means for filling said fluid container, and means for varying the cubical capacity of said fluid container, said piston being adapted to prevent the passage of water through said cylinder from said water conductor and to prevent the passage through said cylinder of fluid from said fluid container, 115 120 125 130

2. The combination with the hull of a ship having an aperture formed through its bottom adapted to communicate with the free water in which the ship may float, of a water conductor covering and communicating at one end with said aperture, means interposed in said conductor for straining the water flowing into said conductor, a pressure cylinder communicating at one end with the opposite end of said conductor, a floating piston in said pressure cylinder, a fluid container communicating at one end with the opposite end of said pressure cylinder, an internal fluid pressure gage communicating with the opposite end of said fluid container, means for filling said fluid container, means for varying the cubical capacity of said fluid container, said piston being adapted to prevent the passage of water through said cylinder from said conductor, and to prevent the passage of fluid through said cylinder from said fluid container.

3. The combination with the hull of a vessel having an aperture formed in its bottom adapted to communicate with the free water in which the vessel may float, of a water conductor adapted at one end to cover and communicate with said aperture, a pressure cylinder communicating at one end with the opposite end of said conductor, the bore of said pressure cylinder being reduced at its opposite end, a floating piston within said pressure cylinder, said piston being reduced in diameter at one end, said reduced end fitting closely the reduced portion of the bore of said cylinder, the larger end of said piston fitting closely the larger portion of the bore of said cylinder, a fluid container communicating at one end with the reduced bore of said cylinder forward of said piston, an internal fluid pressure gage communicating with the opposite end of said fluid container, means for filling said fluid container, means for varying the cubical capacity of said fluid container, said piston being adapted to prevent the passage through said cylinder of water from said conductor, and to prevent the passage through said cylinder of fluid from said fluid container.

4. The combination with the hull of a

vessel having an aperture formed in its bottom for the intake of water from the free body in which the ship may float, of a water conductor adapted at one end to cover said aperture and to receive water through the same, means interposed in said conductor for stopping the flow of water therethrough, means interposed in said conductor for straining the water flowing inward therethrough, a pressure cylinder communicating at one end with the opposite end of said conductor, a floating piston in said cylinder, means for blowing the sediment out of said straining means, a fluid container communicating at one end with the opposite end of said cylinder, an internal fluid pressure gage communicating with the opposite end of said fluid container, a cup or funnel mounted upon and secured to said fluid container for filling the same, a cover for said cup or funnel, a pressure chamber communicating with and forming part of said fluid container, a piston within said chamber, means for operating the latter piston for arbitrarily varying the cubical capacity of said fluid container, and gate valves for closing said fluid container at suitable points to permit repairs.

5. The combination with the hull of a vessel having an aperture formed therein below the water line adapted to admit water at hydrostatic pressure only from the body in which the vessel floats, of a water conductor communicating at one end with said aperture and covering the same, a fluid container, a pressure gage connected to one end of said container, and means for closing the opposite ends of said water conductor and of said container and for transmitting pressure from water in said conductor to fluid in said container, said transmitting means being adapted to be operated by water at hydrostatic pressure only.

In testimony whereof, we hereunto affix our signatures in presence of two witnesses.
